UNITED STATES PATENT OFFICE.

DAVID T. WILLIAMS, OF PATERSON, NEW JERSEY, ASSIGNOR TO STANDARD STOKER COMPANY, INC., OF WILMINGTON, DELAWARE, A CORPORATION OF DELAWARE.

AUTOMATIC STOKER.

1,142,293.

Specification of Letters Patent. Patented June 8, 1915.

Application filed October 29, 1913. Serial No. 798,009.

To all whom it may concern:

Be it known that I, DAVID T. WILLIAMS, a subject of the King of England, residing at Paterson, in the county of Passaic and State of New Jersey, have invented certain new and useful Improvements in Automatic Stokers, of which the following is a specification.

In certain furnaces where a conduit, pipe or other conveying means extends more or less into the space of the furnace above the grate, for instance, the delivery portion of an automatic stoker of the class which feeds the fuel upwardly through the fire, it is found that the intense heat of the fire makes it essential to protect such conveying means by some form of guard. The various types of guards heretofore suggested for this purpose have been found unsuitable, principally because they were not adapted to withstand the destructive action of the heat themselves and required such frequent replacement as to make their maintenance expensive and troublesome.

My object is to provide a guard which shall be substantially proof against the destructive influence of the fire, comparatively simple and inexpensive in construction, adapted to be readily fitted in working position and designed to promote the proper disposition of the fuel, especially in the vicinity of the means whereby it is elevated to the level of the fuel bed.

My invention consists in the novel construction and arrangement of a grate, a fuel conveying means and a guard substantially as hereinafter set forth and finally embodied in the clauses of the claims.

The invention consists, further, in certain details of construction designed to carry forward the objects of the invention in a manner at once practical, involving simplicity and economy of construction, and producing a high degree of efficiency in actual use.

Referring to the accompanying drawings, wherein the invention is fully illustrated, Figure 1 is a vertical, substantially central, longitudinal sectional view of a locomotive fire-box and stoking mechanism provided with my improvement; Fig. 2 is a plan view of the improvement, other parts appearing in Fig. 1 being also shown, partly in full and partly in broken lines; Figs. 3 and 4 are front and side elevations of one

of the two sections of the guard; and, Fig. 5 is a detail showing how the fixed central bar of the grate is formed and supported.

In said drawings, *a* is the fire box, *b* its back sheets and *c* the mud-ring. The grate 60 includes the longitudinal central fixed bar *d* and the rocking bars *e* and *e'*, the former of which are journaled in the usual manner, each at one end in the central bar *d*. Said central bar, in order to accommodate 65 the fuel conveying means (to be described), is formed with its rear end bifurcated, as at *d'*, the two members of its forked or bifurcated portion being supported on the brackets *f* bolted or otherwise attached to 70 the mud-ring. The grate bars *e'*, as will appear, may be pivotally supported at one end on the structure constituting the essential feature of my invention. The tubular conducting means through which the fuel is 75 forwarded and finally elevated through the plane of the bed of burning fuel (in the adaptation shown, substantially through such bed itself) is shown as including the horizontal and vertical tubular sections *g* 80 and *h* communicating with each other and suitably supported, the section *h* extending up through the recess formed in the bifurcation of the rear portion of the central grate bar *d*. In the sections *g* and *h* are 85 shown the revoluble screws *i* and *j* for forwarding the fuel through the conducting means to the upper or discharge end of the section *h* where it either spills over said discharge end of section *h* onto the grate or is 90 distributed over the fire, according as the blast device *k* is not or is operating; the means for rotating said screws, forming no part of this invention, does not require 95 description.

In the preferred form of the invention, I provide a structure like that shown best in Figs. 2, 3 and 4, the same including an upstanding wall *l* that is U-shaped in plan and sloping or inclined upwardly throughout the 100 whole extent thereof, a horizontal platform *m* surmounting the wall *l* and provided with an opening or throat *n* to receive the section *h* of the conveying means, and a base portion *o*. The general formation of this structure is such that when in position as shown in Fig. 1, it forms a space *p* around the portion of the section *h* that projects above the grate and well up toward the top thereof, which space, being open downwardly, forms 110

a chamber for a body of air to insulate the said portion of the section *h* from the heat of the burning fuel-bed. The wall *l* is formed substantially throughout its whole extent with slots *q* or other form of openings which give it a substantially foraminous character, the disposition of such slots or openings being preferably that shown in the drawings; similar slots or openings *q* may be formed in the platform *m* wherever necessary. The base *o* includes in the present instance an upright wall portion *o'* which merges into the wall *l* and a flat portion *o''* inclined forwardly and downwardly at about the same angle as that of the grate structure. In order that the guard may be readily assembled with the grate structure and the conveying means it is divided centrally into two sections, the said sections having interior projections *r* through which, after said sections have been placed in embracing relation to section *h* of the conveying means, bolts or other clamping means *s* may be passed to hold the sections together. The guard is supported, when in working position, by the central fixed grate bar *d*, the base *o* of the guard resting upon the forked rear portion *d'* of said grate-bar, and it is held from sliding forward by the sockets or recesses *t* in forward extensions *o'''* of its base being engaged with two trunnions or lugs *u* on the grate-bar *d*. (As shown, the extensions *o'''* are preferably formed foraminous). The base *o* may be provided with lugs or trunnions *v* affording bearings for the shorter grate bars *e'*. In view of the foregoing it will be seen that the guard, which affords a lateral support to the body of fuel on the grate, forms around the part of the section *h* of the conveying means that projects above the grate a downwardly open air chamber for insulating said part from the heat of the body of fuel and that a copious supply of air is constantly fed to the chamber or space thus formed (and discharged therefrom through the passages in the guard, thus preventing the same from becoming overheated) because the fuel support itself affords air passages extending vertically therethrough from below and discharging upwardly into said space, the same existing both inside and directly outside of the wall formed by the rear bifurcated portion *d'* of the fuel-support (see Fig. 1).

The sloping or inclined formation of the guard promotes the piling of the fuel around the guard in a manner calculated to cause the fuel to cover the openings in the guard when a fresh fire is started and the fuel-bed is therefore low, at which time if it were not for this stacking or piling of the fuel well up around the guard the openings therein would allow the draft to enter the fire-box over the fuel, instead of through it, which of course would have a deadening effect on the fire, at least in the vicinity of the introduction of the fuel.

Having thus fully described my invention, what I claim as new and desire to secure by Letters Patent is:—

1. The combination of a grate, a fuel conveying means having its delivery portion arranged over the grate, and an upstanding guard affording a lateral support for the fuel on the grate and forming with said delivery portion a downwardly open space and having passages discharging laterally from said space, and said grate having an air passage extending upwardly therethrough from below and discharging into said space.

2. In combination, with a furnace grate including grate members one of which is fixed, a fuel conveying means having its delivery portion extending from below to a point above the grate, and a passaged guard for said delivery portion of the conveying means carried by said fixed grate member, some of the remaining grate members being supported by the fixed grate member and others by the guard.

3. In combination, with a furnace grate including grate members one of which is fixed, a fuel conveying means having its delivery portion extending from below to a point above the grate, said fixed grate member being formed to embrace said delivery portion of the conveying means, and a passaged guard for said delivery portion of the conveying means extending around the same, some of the remaining grate members being supported by the fixed grate member and others by the guard.

In testimony whereof I affix my signature in presence of two witnesses.

DAVID T. WILLIAMS.
